UNITED STATES PATENT OFFICE.

JOHN O. CURRIER, OF SANGERVILLE, MAINE, ASSIGNOR TO LEWIS E. CURRIER, OF SAME PLACE.

DISK-CULTIVATOR.

SPECIFICATION forming part of Letters Patent No. 333,927, dated January 5, 1886.

Application filed July 22, 1885. Serial No. 172,296. (No model.)

To all whom it may concern:

Be it known that I, J. O. CURRIER, of Sangerville, in the county of Piscataquis and State of Maine, have invented an Improved 5 Disk-Cultivator, of which the following is a specification.

The special object of the invention is to furnish the public with a horse-hoe or disk-plow cultivator, which can be conveniently handled and adjusted by the workman or any person not a mechanical expert.

Figure 1 of the drawings is a plan view showing the general relation of the parts, their construction, and arrangement. Fig. 2 15 is a side elevation showing the pendent bearings for the disk-wheels and their connection with the adjusting-rod.

In the drawings, A represents the disk-cultivators, which are placed at the usual or desired obliquity to the line of draft, as shown in Fig. 1 of the drawings.

B are hangers or pendent bearings, in which are journaled the bolts on which the disks turn. The hangers B are attached at 25 the top to a cross-bar, C, having the slots c c, one near each end, and by the clamping-bolts c', so that they may be adjusted to a greater or less distance apart to suit the width at which they are expected to cultivate.

30 D is the cultivator beam or tongue, on which is usually employed an evener, E, pivoted thereto.

F F are the handles, which are fastened to the sides of beam D, and provided with the usual spacing round and iron brace.

35

G is an eyebolt, through whose aperture or eye pass the crossing-rod H H. The latter have eyes at the rear ends, which joint with eyebolts b on the hangers B B, as shown in Fig. 2 of the drawings. By loosening the 40 clamps c' G the rods H H are movable to correspond with the lateral adjustment of the disk-hangers B.

I am well aware that the parts of my cultivator are not separately new, but only my way 45 of combining and arranging the parts to form a convenient and useful implement; hence

What I claim as new, and desire to protect by Letters Patent, is—

In a disk-cultivator, the combination of a 50 beam or tongue carrying eyebolts G, a cross-bar, C, slotted near each end, hangers B B, carrying eyebolts b c', and brace-rod H H, hinged to eyebolts b, whereby the hangers and brace-rod may be correspondingly adjusted 55 with the disks to regulate their distance apart or their obliquity, in the manner described.

JOHN O. CURRIER.
